B. STEBELTON

DEMOUNTABLE RIM

Filed June 1, 1923

Inventor
Boyd Stebelton,

By *Ernest Talbert*

Attorney

UNITED STATES PATENT OFFICE.

BOYD STEBELTON, OF BALTIMORE, OHIO.

DEMOUNTABLE RIM.

Application filed June 1, 1923. Serial No. 642,735.

To all whom it may concern:

Be it known that BOYD STEBELTON, a citizen of the United States of America, residing at Baltimore, in the county of Fairfield and State of Ohio, has invented new and useful Improvements in Demountable Rims, of which the following is a specification.

The object of the invention is to provide a sectional demountable rim in which yielding members are provided to secure the sections in attached position so that the sections may be readily disconnected after removal of the rim from the wheel.

With this object in view the invention consists in a construction and combination of parts of which a preferred embodiment is shown in the accompanying drawings, wherein:—

Figure 1 is a perspective view of the invention.

Figure 2 is a side elevational view.

Figure 3 is a transverse sectional view on the line 3—3 of Figure 2.

The invention comprises the complementary rim sections 1 and 2 consisting of continuous annular rings provided with the peripheral flanges 3 which may be either of the clincher form or, as shown, shaped for the reception of straight-side tires. Internally the section 2 is circumferentially beveled, as indicated at 4, from its inner surface to its inner edge, while the section 1 is provided with a cross sectional wedge-shaped portion 5 adapted to fit snugly in the bevel of the section 2, inclined faces 6 and 7 of the wedge-shaped and

beveled portions contacting throughout their widths.

On the inner surface of the section 2 and between its edges, there is formed an annular and angular groove 8 adapted for engagement with the heads 9 of spring clips 10 which are disposed transversely of the two ring sections and are secured to the inner surface of the section 1, as indicated at 11. The spring clips serve to hold the ring sections in connected relation and they may be readily disassembled by the insertion of screw-drivers or other appropriate tools under the heads of the clips, thus retracting the heads from the groove and thereby leaving the sections free to be separated.

Having described the invention, what is claimed as new and useful is:—

A demountable rim structure comprising a pair of continuous annular rings, one of which is provided at its inner surface and between its edges with an annular and angular groove, the said ring being beveled from its inner surface to its inner edge, the other ring having a wedge-shaped portion adapted to fit snugly in the bevel of the first mentioned ring, and the second mentioned ring having a plurality of spring clips adapted to be disposed transversely of the first mentioned ring, said clips having heads adapted to engage in the annular groove of the first mentioned ring.

In testimony whereof he affixes his signature.

BOYD STEBELTON.
